CONTROL FOR ELECTRICAL VEHICLE

Edwin O. Stastny, 2122 N. Pasadena Ave.,
Santa Ana, Calif. 92701

Filed Oct. 10, 1972, Ser. No. 296,033

Term of patent 7 years

Int. Cl. D13—03

U.S. Cl. D26—13 R

FIG. 1.

FIG. 2.

FIG. 3.

FIG. 4.

FIG. 1 is a top plan view of a control for electrical vehicle embodying the new design;

FIG. 2 is a side elevational view of the control;

FIG. 3 is a rear elevational view of the same; and

FIG. 4 is a front elevational view of the control.

I claim:

The ornamental design for a control for electrical vehicle, substantially as shown.
